RAILWAY HOPPER CAR CONSTRUCTION

Henry W. Reynolds and Edward C. Roesener,
Roanoke, Va.

Application October 9, 1939, Serial No. 298,542

8 Claims. (Cl. 105—249)

This invention relates to the construction of railway freight cars of the hopper type, ordinarily used for the transportation of coal, sand, gravel and other granular material.

One object of our invention is to provide a car of light weight, having the floor and hoppers constructed of a minimum number of parts, a number of said parts being identical and of such design that they may be fabricated from rectangular sheets without any scrap being left.

Another object of our invention is to provide means for bracing the side walls of the car with a minimum amount of obstruction to power operated buckets used for loading and unloading the car. The brace means employed are of such construction as to offer resistance to distortion when struck by a bucket.

Another object of our invention is to provide a floor and hopper construction which will offer a minimum amount of obstruction to the lading flowing freely out of the car when the hopper doors are opened.

A still further object of our invention is to provide a floor and hopper construction which may be readily assembled as a unit or units and installed in the car.

Other objects and advantages of our invention will appear from the following detail description of the attached drawings, wherein

Fig. I is a fragmentary view in longitudinal section of a hopper car embodying our invention, the section being taken as indicated by the arrows I—I in Fig. II.

Fig. II is a fragmentary plan section view taken as indicated by the arrows II—II in Fig. I.

Fig. III is a fragmentary view in transverse section, on a larger scale, taken as indicated by the arrows III—III in Fig. II.

Figs. IV and V are views like Figs. III and I respectively, showing a modified embodiment of our invention.

Figs. VI, VII, VIII and IX, are sections on an enlarged scale, taken respectively as indicated by the arrows VI—VI, VII—VII, VIII—VIII, and IX—IX, in Fig. III.

Figs. X and XI are fragmentary views, on a larger scale, like Figs. I and II, showing a further modified embodiment of our invention.

Referring now more specifically to the drawings; Figs. I to III inclusive, the center sill designated comprehensively by the numeral I comprises channel sections 2 with the flanges disposed toward each other; top cover plate 3 and bottom tie bars 4. While the center sill is shown comprising channel sections, Z-bar sections could

be as equally well employed, in which case the top cover plate 3 would not be required. One of the side sills is indicated at 5; the side wall at 6 and the side wall supporting stakes at 7. The upper end of the side stakes 7 are connected by a top rail 8. The end slope sheets of the car, indicated by the numeral 14, are integral with the end wall sheets. All of the foregoing is more or less usual practice in the art.

10 The floor construction consists of the end slope sheets 14, transverse ridge sheets 9, longitudinal hood sheets 15, together with a plurality of hoppers disposed on each side of the center sill. The transverse ridge sheets 9 extend from side wall to side wall and are rigidly secured to the side walls and to the side sills 5 by welding, indicated by the numeral 10. Where the transverse ridge sheets overlie the center sill they are cut out to fit the center sill and are rigidly secured thereto by welding, indicated by the numeral 12.

15 Extending longitudinally of the car and overlying the center sill we have provided longitudinal hood sheets, all of the same design and fabrication, permitting them to be manufactured in large quantities with substantial saving in costs. These longitudinal hood sheets are rigidly secured to the transverse ridge sheets 9 and to the end slope sheet 14 by welding, as indicated at 16.

20 Disposed on each side of the center sill we have provided a plurality of hoppers, each comprising an inside side sheet 17, and an outside side sheet 18, and a slope sheet 19. The hopper door and door frame have been omitted from the drawings for the purpose of showing more clearly the embodiments of our invention. The hopper slope sheet 19 is rigidly secured to the inside hopper side sheet 17 and to the outside

25 hopper side sheet 18 by welding as indicated by the numeral 20. The inside hopper side sheet 17 is likewise rigidly secured to the longitudinal hood sheet 15 by welding, indicated at 21. The outside hopper side sheet 18 is secured in a like manner to the side sill 5, as indicated by the numeral 22.

30 The hopper slope sheet 19, of the hoppers at the ends of the car are rigidly secured to the end slope sheets 14, by welding, as indicated at 23, while on the hoppers intermediate of the end hoppers the slope sheet 19 is secured in a like manner to the transverse ridge sheet 9, as indicated at 24.

35 Referring now more particularly to Figs. I, III, VI, VII, VIII and IX, we have provided novel and new brace means for the side walls of the car.

The brace means comprise an integral cast brace 25, having substantially vertical flanges 26 engaging the side walls 6 and rigidly secured thereto and to the coacting side stakes 7 by means of rivets. The brace 25 where it engages and rests upon the transverse ridge sheet 9, has a flared out portion or foot, indicated by the numeral 28, conforming to the top and sides of the peaked transverse ridge sheet. The rivet 29 is provided in the bottom of the brace 25 for the purpose of aligning the side wall sheets 6 in a vertical plane until the foot of the brace can be rigidly secured to the transverse ridge sheet by welding, indicated at 27. The brace 25 comprises a hollow U section with converging legs 30 and 31, one of the legs, as indicated by the numeral 32, being extended and terminating in a bulb section 33. A plurality of openings 34 are provided in one of the legs of the U section for the purpose of providing anchorage for the cores and for removing the cores from the casting after the casting has been removed from the mould.

Figs. IV and V disclose a modified embodiment of our invention wherein the longitudinal hood sheets are integral with the inside hopper side sheets; and the transverse ridge sheets and the integral end wall and end slope sheets are integral with adjacent hopper slope sheets. The inside hopper side sheets 17 are inclined inwardly and upwardly over the center sill forming the sides of the longitudinal hood sheets 15 and are rigidly secured to each other by welding at the top of the peak as indicated by the numeral 35. The hopper slope sheet 19 of the hoppers at the ends of the car are integral with the integral end wall and end slope sheets 14. The hopper slope sheet 19 of the hoppers intermediate of the end hoppers is integral with a transverse ridge sheet 9. These embodiments reduce the number of pieces in the floor structure of the car with a corresponding decrease in the number of joints or seams.

Figs. X and XI disclose a further embodiment of our invention wherein we have provided end caps 36 for the longitudinal hood sheets 15. These caps are provided for two purposes. In the fabrication of the longitudinal hood sheets, when the end caps are used, no scrap is formed, the sheets being cut from rectangular plates. Further, when the longitudinal hood sheets are made in one piece, without the end caps, it is often difficult to secure a proper close fit between the longitudinal hood sheets and the transverse ridge sheets and the integral end wall and end slope sheets to which the longitudinal hood sheets are welded. With the embodiment disclosed, the longitudinal hood sheets can be rigidly secured to the inside hopper side sheets 17 as indicated at 21; the hood sheets and inside hopper side sheets can then be placed in position; the end caps 36 then placed in position and rigidly secured to adjacent transverse ridge sheets 9 and to adjacent integral end wall and end slope sheets 14 by welding, as indicated at 16. The seam between the hood sheet 15 and the end caps 36 is a welded lap seam indicated at 37, which takes care of any variations in the required overall length of the hood sheet that may be necessary to secure a close fit between the hood sheet and the transverse ridge sheets and the integral end wall and end slope sheets.

To secure the transverse ridge sheets 9 and the integral end wall and end slope sheets 14 in proper relationship to the center sill 1, and other associated parts of the car until the welding

hereinto previously referred to can be performed, we have provided a flange 38 which is secured to the center sills by the rivets 39. The flanges 38 are formed as follows: When the transverse ridge sheets and the integral end wall and end slope sheets are cut out where they fit over the center sill, as indicated at 40, a portion of the cut-out section is cut off and the remainder turned out to form a flange 38.

In the assembling of the car, the floor members comprising the transverse ridge sheets; the longitudinal hood sheets; and the hoppers, as units or the individual members thereof, may be assembled on a form or template and then placed in position in the car and rigidly secured to the car by welding.

A modified method of assembling consists of rigidly securing the transverse ridge sheets and the longitudinal hood sheets in position in the car by welding; installing the hoppers as units and rigidly securing them to the car by welding.

A still further modified method of assembling the car consists of rigidly securing the transverse ridge sheets and the end slope sheets to the center sill by means of the rivets 39; welding the inside hopper side sheet to the longitudinal hood sheets and then placing the longitudinal hood sheets in position over the center sill and securing the inside hopper side sheets to the center sill by means of tie bar 4; rigidly securing the side sills and the cast brace means to the side walls and then placing the side walls in position; rigidly securing the cast brace means to the transverse ridge sheets by means of the rivets 29; placing the outside hopper side sheets and the hopper slope sheets in position; welding the transverse ridge sheets to the side walls and to the side sills; welding the longitudinal hood sheets to adjacent transverse ridge sheets and to adjacent integral end wall and end slope sheets; welding the side walls to the integral end wall and end slope sheets; welding the cast brace means to the transverse ridge sheets; welding the outside hopper sheets to the side sills and the hopper slope sheets; welding the hopper slope sheets to the inside hopper side sheets and to adjacent transverse ridge sheets to adjacent integral end wall and end slope sheets.

Where the longitudinal hood sheets and caps are employed they are first welded to the transverse ridge sheets and to the integral end wall and end slope sheets and then to the hood sheets.

It will be readily seen that we have provided a hopper car of comparatively light weight, having a floor and hopper construction consisting of a relatively few parts. In the embodiment disclosed in Figs. I to III inclusive, the two integral end wall and end slope sheets 14 of the car are the same; the hoppers as units are the same; and the longitudinal hood sheets 15 are also the same. The inside hopper side sheets; the outside hopper side sheets; and the slope sheets are the same on all hoppers and may be cut from rectangular sheets with a minimum loss as scrap. In the embodiment disclosed in Figs. X and XI the longitudinal hood sheets and the end caps are the same and may be cut from rectangular sheets with no loss as scrap.

The design of the cast brace 25, in addition to being such that it offers a minimum amount of obstruction to power operated buckets used for loading and unloading the car, is of such construction that it offers a maximum resistance to distortion by being struck by a bucket.

The employment of few seams in the floor con-

struction and in the hoppers and such seams being welded provides a rigid construction which offers very little, if any obstruction to the lading of the car flowing freely out of the bottom of the car when the hopper doors are opened.

The construction of the floor and hoppers is such that several methods of assembling may be employed, which will greatly reduce the time and cost of building the car.

Having thus described our invention, we claim:

1. In a railway hopper car: the combination of a center sill; side sills; side walls; integral end wall and end slope sheets; transverse ridge sheets recessed to receive the center sill and resting thereon, the said transverse ridge sheets extending from side wall to side wall and directly welded to said side walls, side sills and center sill; brace means rigidly secured to the side walls and the transverse ridge sheets; longitudinal hood sheets overlying the center sill and rigidly secured to adjacent transverse ridge sheets and to adjacent integral end wall and end slope sheets by welding; hoppers, comprising an inside and an outside side sheet and a slope sheet, said hopper sheets having their adjacent portions rigidly secured to each other by welding; said hoppers rigidly secured to the car by welding.

2. In a railway hopper car: a plurality of members comprising side sills; center sill; side walls; integral end wall and end slope sheets; transverse ridge sheets extending from side wall to side wall and contacting same, said transverse ridge sheets being recessed to receive said center sill and resting thereon; longitudinal hood sheets overlying the center sill; and hoppers disposed on each side of said center sill, each comprising an inside and outside side sheet and a slope sheet; the adjacent portions of said members being directly secured to each other by welding.

3. In a railway hopper car: the combination of a center sill; side sills; side walls; integral end wall and end slope sheets; transverse ridge sheets recessed to receive said center sill and resting thereon and directly welded thereto, the ends of the transverse ridge sheets rigidly secured to the side walls and the side sills by welding; brace means rigidly secured to the side walls and the transverse ridge sheets; hoppers, comprising an inside and an outside side sheet and a slope sheet; adjacent portions of said hopper sheets rigidly secured to each other by welding; the outside hopper side sheets rigidly secured to the side sills by welding; the inside hopper side sheets inclined upwardly and inwardly over the center sill to form longitudinal hood sheets; the edges of the inside hopper side sheets being rigidly secured to each other by welding where they come together in a peak over the center sill; said longitudinal hood sheets rigidly secured to adjacent transverse ridge sheets and to adjacent integral end wall and end slope sheets by welding; said hopper slope sheets being integral with adjacent integral end wall and end slope sheets and with adjacent transverse ridge sheets.

4. In a railway hopper car: the combination of a center sill; transverse ridge sheets recessed to receive the center sill and resting thereon and directly welded thereto; and hoppers, each com-

prising an inside side sheet, an outside side sheet, and a slope sheet, the inside side sheet inclined upwardly and inwardly over the center sill to form a longitudinal hood sheet, the edges of the inside side sheets of adjacent hoppers on opposite sides of the center sill being rigidly secured to each other by welding where they come together in a peak over the center sill.

5. In a railway hopper car: the combination of side walls; a center sill; and hoppers each comprising an inside and an outside side sheet and a slope sheet; transverse ridge sheets extending from side wall to side wall and secured thereto by welding, said transverse ridge sheet having a side wall inclined downwardly forming the slope sheet for said hoppers, the transverse ridge sheets being recessed to receive said center sill and resting thereon and welded directly thereto.

10 6. In a railway hopper car: a center sill; side walls; transverse ridge sheets extending from side wall to side wall and secured thereto by welding; hoppers, each comprising an inside and an outside side sheet and a slope sheet; integral end wall and end slope sheets inclined downwardly forming the slope sheet for said hoppers, said integral end wall and end slope sheets secured to said side walls and to said inside and outside hopper sheets by welding; the said transverse ridge sheets being recessed to receive said center sill and resting thereon and welded directly thereto.

7. In a railway hopper car: the combination of a center sill; longitudinal hood sheets overlying the center sill; side walls; transverse ridge sheets extending from side wall to side wall and secured thereto by welding; integral end wall and end slope sheets; and hoppers disposed on each side of said center sill; said hoppers comprising an inside and an outside side sheet and a slope sheet rigidly secured to each other and to the car by welding; the said hopper slope sheet of the end hoppers being integral with an end wall and end slope sheet; the said hopper slope sheet of the hoppers between the end hoppers being integral with a transverse ridge sheet; said transverse ridge sheets being recessed to receive said center sill and resting thereon and welded directly thereto.

8. In a railway hopper car: the combination of a center sill; side walls; integral end wall and end slope sheets rigidly secured to said side walls by welding, transverse ridge sheets recessed to receive said center sill and resting thereon and rigidly welded thereto and to the side walls; cast brace members rigidly secured to the transverse ridge sheets by welding; hoppers comprising inside side sheets; longitudinal hood sheets rigidly secured to the top portion of the inside hopper side sheets, to adjacent transverse ridge sheets, and to integral end wall and end slope sheets by welding; separate means comprising rivets securing the transverse ridge sheets, the cast brace members and the inside hopper side sheets in position while the welding referred to is being performed.

HENRY W. REYNOLDS.
EDWARD C. ROESENER.
